UNITED STATES PATENT OFFICE.

WILLIAM A. DOUGLAS, OF UTICA, NEW YORK.

SASH-LOCK.

No. 802,918.

Specification of Letters Patent.

Patented Oct. 24, 1905.

Application filed September 29, 1904. Serial No. 226,434.

To all whom it may concern:

Be it known that I, WILLIAM A. DOUGLAS, of Utica, in the county of Oneida and State of New York, have invented certain new and useful Improvements in Sash-Locks; and I do hereby declare that the following is a full, clear, and exact description of the invention, which will enable others skilled in the art to which it appertains to make and use the same, reference being had to the accompanying drawings, and to the figures of reference marked thereon, which form part of this specification.

The object of my invention is to provide a sash-lock which is automatic in its locking operation, simple in construction and of easy operation, and which is applied to the sash in such a manner as to be not only unobjectionable, but entirely desirable.

In the drawings which accompany and form a part of this specification, Figure 1 shows a front view of a sash having my sash-lock applied, a portion of the frame, however, of the sash being broken out to reduce the size of the figure. Fig. 2 shows a cross-sectional view of the same. Figs. 3^a and 3^b show two partial longitudinal sections or views taken in different planes. Fig. 4 shows a side elevation of the lock with the front plate of the casing removed. Figs. 5^a and 5^b show longitudinal horizontal sections with the mechanism in each part operated to different positions. Fig. 6 shows a modified form of construction with the rear plate of the casing removed. Figs. 7^a and 7^b show longitudinal vertical sections of the same with the mechanism in each part operated to a different position. Fig. 8 shows a plan view of the sliding catches employed in the modified form of construction shown in Figs. 6 and 7^a and 7^b, together with the springs which operate the catches and the frame or fixed catch with which they engage. Fig. 9 shows another modified form of construction applied to a window-sash. Fig. 10 shows a longitudinal sectional view of the same with the parts in locked or engaged position. Fig. 11 shows the same in the unlocked position. Fig. 12 shows the fixed catches applied to the window sill or frame. Fig. 13 is a cross-sectional view through the lock and sash.

Referring to the reference-figures in a more particular description of the device, 1 indicates the box-like casing, which is adapted to be inlet into the sash-frame 2 and secured therein and is provided through its outer

wall with a hand-opening 3. Mounted in the casing and arranged to stand normally partially in the hand-opening 3 or opposite to a portion of the hand-opening 3 is a movable or retiring handle 4, which includes downwardly-extending end portions 4^a, which engage on the end walls of the case 1 and operate as a guide or slide for directing the movement of the handle. In the lower portion of the casing there is provided what might be termed an "inner" casing 5. This casing as to its top 5^a furnishes a closure for the lower side of the hand-opening 3 and at its ends provide openings or passages for the lower end of the sliding parts 4^a. In the ends of the inner casing 5 there are provided pivoted rollers 6. Attached to the lower ends of the sliding parts 4^a and passing around the roller 6 is a band or strap 7, preferably of flexible metal, which extends and is attached to the sliding catch 8. For drawing the catches 8 toward each other into engaging position with the casing or frame catch 9 there is provided a pair of springs 10, which are secured at their respective ends to hooks or other fixtures on the slides 8 at each end of the casing. The casing or frame catch 9 is a spear-head construction mounted and secured on a plate 11, adapted to be secured to a window-frame, either the sill or the top of the frame, as the lock is applied to the lower sash, the upper sash, or both, of a window.

It will be noted that the springs 10 draw the catches 8 at the opposite ends of the casing toward each other and into securing engagement with the frame-catch 9 and at the same time draw down the handle 4. If the sash-lock is applied to the lower sash of a window to operate the same, the operator places his fingers in the hand-opening 3 below the handle 4 and lifts up. In so doing the handle is moved from the position shown in Figs. 1, 2, and 3^a, where the catches 8 are in securing position, to the position shown in Fig. 3^b, where the catches are released. Continued upward pressure on the handle 4 then serves to raise the sash and open the window. Of course when the sash-locks are applied at the top of the window on the upper sash a downward movement of the operator's hand accomplishes the unlocking of the lock and the opening of the window in the same manner. When the sashes are closed, the spear-head-frame catch 9 enters between the adjacent ends of the sliding catches 8, forcing them temporarily apart until the completely-

closed position is reached, when they are then moved into engaging and securing position.

In the modified form of construction shown in Figs. 6 and 7 a somewhat similar casing 20 is provided, having in its face side the hand-opening 21 and within the casing provided with the vertically-movable handle 22. This handle, similar to the others, is provided with end portions 22^a, which engage in the 10 end of the case and direct the movement of the handle 22 and are provided with inclined projections 22^b. These projections are adapted to engage the upper ends, respectively, of the levers 23, pivoted in the casing at 24. 15 The lower end of these levers engage with the sliding catch-pieces 25, which operate similar to those heretofore described. These catch-pieces 25 are mostly received within the inner casing 26, the upper wall 26^a of which 20 serves as a closure for the lower side of the hand-opening 21 in the case. The catches 25 are drawn toward each other by springs 27, similar to those heretofore described, secured at their opposite ends to the sliding catches 25, respectively, in each end of the casing. 25 These catches are adapted to engage with the similar spear-head-frame catch-piece 28 to that heretofore described. To move the handle 25 into its lower position when not forcibly moved otherwise, there is provided a 30 spring 29, arranged in the upper portion of the case and preferably secured at 30 to the handle 22 and having its free ends adapted to engage the top wall of the case. This spring 35 operating to force downwardly the handle 22 serves particularly to move the wedging projections 22^b out of their operative positions, so as to allow the catches 8 to slide toward their middle position and into engaging or securing position.

In the modified form of construction shown in Figs. 9 to 13, inclusive, there is provided a construction which is adapted to a narrow window-sash and which is adapted to operate 45 in connection with two fixed hooks or catch projections provided on the window-frame. In this modified form of construction there is provided a box-like casing 40, adapted to be secured in a recess in the window-sash in a 50 somewhat similar manner to that heretofore described. In connection therewith there is provided a movable handle 41 in the nature of a loop, which at each end is provided with parallel portions 41^a. These portions 41^a are 55 adapted to engage the end of the casing and serve as slides to direct the movement of the handle. Within the casing the handle is provided with a cross-bar 41^b. To this cross-bar is attached the one end of the straps or bands 60 42, which, passing around the fixed rollers 43, are attached at the other end to the sliding catch-pieces 44. These catch-pieces 44 are adapted to engage with the hook-like projection-catches 45, mounted on a plate 46, adapted 65 to be secured to the window-sill or window-frame.

Between projections on the adjacent ends of the sliding catches 44 there is introduced an expansion-spring 47, which serves to force the catches 44 apart when not otherwise held and into engagement with the frame-catches 45. There are provided in the lower side of the main casing 40 suitable openings to allow the catches 45 to enter. It will be noted that when force is applied to the handle 41 to move it in the direction that the sash will move in opening the window that the first operation is to draw back the catches 44, releasing the sash, while a continued movement will serve to open the window. In closing the window the inclined heads of the frame-catches 45 will serve to force back the sliding catches 44, allowing the catch-shoulder to pass to a position where it can be engaged by the sliding catch 44.

It is evident that numerous other modifications and changes in and from the construction herein described can be made without departing from the spirit of my invention.

What I claim as new, and desire to secure by Letters Patent, is—

1. The combination in a sash-lock of a casing, a handle movable in the same direction as the sash, a locking-catch mounted in the casing, a roller journaled in the casing, a flexible connection between the locking-catch and the handle passing around the roller, a spring for moving the catch into locking position, and a fixed casing-catch with which the locking-catch is adapted to engage, substantially as set forth.

2. The combination in a sash-lock of a casing having a hand-opening, a handle mounted to slide vertically in the casing and adapted to take a normal position opposite the hand-opening, a locking-catch mounted in the casing and adapted to engage a suitable fixed catch-piece provided on the window-frame, a spring for moving said locking-catch into engaging position, and a connection between the said handle and the locking-catch arranged to allow the catch to move independently of the handle when forced by the fixed catch-piece, substantially as set forth.

3. The combination in a sash-lock of a casing having a hand-opening in its side, a movable handle mounted in the casing and arranged to slide vertically therein and to normally occupy a position partially in front of the hand-opening, a pair of sliding catches mounted in the casing to move laterally into engaging position, an operative connection between the sliding catches and the handle arranged to allow the catches independent operation from the handle, springs for moving said catches into engaging position, and a fixed frame catch-piece with which said sliding catches are adapted to engage and adapted to force the catches into retired position, substantially as set forth.

4. The combination in a sash-lock of a cas-

- ing having a hand-opening and a catch-inclosing section between the opening and the bottom of the casing, locking-catches arranged in said inclosing section, a handle mounted to slide vertically in casing and to take a normal position opposite the hand-opening and extending at its ends into portions of the casing at each side of the hand-opening, operative connections between the handle and said catches respectively arranged within the portions of said casing at each side of the hand-opening and said catch-section, a spring for operating the catches to close position and a window frame or casing catch, substantially as set forth.
5. In a sash-lock for windows, the combination of a window-frame, a sash mounted therein, a fixed catch applied to the window-frame, a lock-casing secured to the sash, a movable catch arranged in the casing, a handle movably mounted in the casing, and a flexible con-

nection located in the casing and connecting the movable catch and handle aforesaid.

6. In a sash-lock for windows, the combination of a window-frame, a sash mounted therein, a fixed catch applied to the window-frame, a lock-casing secured to the sash, oppositely-slidable catches arranged in the casing to engage the fixed catch, a handle slidably mounted for movement at an angle to the line of movement of the sliding catches, springs co-operating with the movable catches, and flexible connections connected at one end with the handle and at the opposite end with a respective one of the movable catches. 35

In witness whereof I have affixed my signature, in presence of two witnesses, this 27th day of September, 1904.

WILLIAM A. DOUGLAS.
